[57] CLAIM

The ornamental design for a combined hand-held plate and beverage holder, as shown and described.

DESCRIPTION

FIG. 1 is a top perspective view of a combined hand-held plate and beverage holder showing my new design. The broken line showing of the hand and cup is for illustrative purposes only and forms no part of the claimed design;

FIG. 2 is a bottom perspective view thereof; and FIG. 3 is another top perspective view identical to FIG. 1 without the broken lines.

FIG. 3
